UNITED STATES PATENT OFFICE.

WILHELM HARTMANN, OF FULDA, GERMANY.

BAND-SAW FOR SAWING METAL.

SPECIFICATION forming part of Letters Patent No. 650,936, dated June 5, 1900.

Application filed July 18, 1899. Serial No. 724,279. (No model.)

To all whom it may concern:

Be it known that I, WILHELM HARTMANN, a subject of the Emperor of Germany, and a resident of Fulda, in the Empire of Germany, 5 have invented a certain new and useful Band-Saw for Sawing Metals, of which the following is a full, clear, and exact specification.

My invention relates to a new and improved "band-saw for sawing metals," and is constructed and operated as set forth in the following specification, of which the accompanying drawings form an inseparable part.

In the drawings, in which similar letters refer throughout to similar parts, Figure 1 shows in side elevation my invention. Fig. 2 is a sectional view thereof on line A B of Fig. 1. Fig. 3 is a plan view of Fig. 1.

Heretofore such machines have been so constructed that it was necessary to continuously advance the object being sawed against the band-saw. In lieu of band-sawing machines, machines were therefore generally employed having an oscillating or pendulum-swing saw working upon the object stationarily fixed, the latter forms alone being susceptible of operation without generating a frictional resistance of such degree as to make the machine unpractical. The fact that until my invention the sawing-machines having the object stationarily fixed were preferably provided with an oscillating or pendulum-swing saw is due to the cause that such alone were sufficiently susceptible of continuously operating upon and freely and simultaneously therewith advancing against the said object. It is therefore with the elimination of such drawbacks that I have invented a band-saw machine in which the object to be sawed is stationarily secured, while the band-saw 35 proper receives a regular cutting motion and in addition thereto and simultaneously therewith an automatic forward movement, the latter in all parts where friction is produced acting in such a manner that straight movement is avoided and exclusively-rotating parts are sliding in their journals, whereby an extremely easy movement is obtained.

In the construction of my invention, therefore, I employ any desired frame, as C, which has transversely mounted therein three parallel main shafts q , p , and p' , while fastened to the forward side of said frame are suit-

able brackets u' and u , forming additional bearings for the forward ends of the shafts aforesaid. These bearings q' q p' p have 55 preferably bearing-balls therein, so as to reduce the friction in the axial movement of said shafts to a minimum, which latter have, as will be seen, a spirally-turning fore-and-rear motion. Mounted on shaft q is a roller 60 b , which, with rollers c and c' , respectively mounted on shafts p and p' , carries the saw-band a , adapted to saw an object fixed on a table or shelf adjacent thereto. Securely fastened to the frame C, projecting rearwardly 65 therefrom, is a shaft-casing t , in which is mounted an axle s' , carrying at its rear end a belt-wheel s and at its forward end a toothed wheel d , having any desired length, while mounted on shaft p is a toothed wheel d' , 70 meshing with wheel d aforesaid, and through which latter the shafts are given a rotary motion, thereby operating the band-saw a , and by which special construction of wheel d its rotary movement can be imparted to wheel 75 d' at whatever position the shaft p may assume. Near the rear end of shaft q is a sleeve r , having studs r' therein, the latter in turn fitting in the prongs of a fork o' , connected with a rod o , suitably mounted in bearings 80 o^2 in the said frame and extending at right angles to said shafts. To one end of said shaft o is connected a band n' , which, passing over suitably-grooved wheels m m' , has on its outer end a weight n , which as the latter 85 descends throws arm o' forward, thereby imparting a forward pressure to said shaft q ; but since the said shaft is rapidly rotating its motion forward loses any direct forward movement and becomes a spiral or twisting 90 action. In order to transmit this spiral action to shafts p and p' , I employ racks k and k' , mounted on vertical axles i i' , which latter are journaled in any suitable supports connected with the frame of the machine. 95 The side of rack k adjacent to shaft q is provided with a forked arm h , having slots g formed therein, and into which latter fit pins f , also carried on sleeve r aforesaid. On the adjoining sides of the racks k k' are meshing toothed quadrants l l' , through which connection, as will clearly be seen, the racks act together. Rack k' is in turn in connection by suitably-forked arms with shafts p and p' , 100

whence it will be seen that any forward movement imparted to shaft *q* will be simultaneously transmitted to the said latter shafts.

5. The operation and advantages of my invention will be clearly understood from the foregoing description and accompanying drawings, when taken in connection with the following statement. Desiring to saw a piece 10 of metal, the same is secured to a suitable table or shelf and the machine thrown in gear, whence the power imparted by pulley-wheel *s* to axle *s'* drives wheel *d*, the latter in turn rotating wheel *d'* on shaft *p*, which carrying- 15 roller *c* operates the band-saw connected therewith, together with rollers *c'* and *b* and their respective shafts. Simultaneously therewith, however, weight *n* continually draws band *n'* downwardly, thereby revolving rod 20 *o*, which latter, through arm *o'*, in connection with shaft *q*, and the latter, through the racks *k* and *k'*, with their meshing quadrants, impart to the said shafts a steady forward pressure, but which in place of developing a direct forward movement thereto is converted 25 through the combination of the independent rotary motion aforesaid therewith into a spirally-advancing forward action, thereby eliminating any frictional resistance arising 30 through a straight movement of said shafts while rotating. By this adjustment the bandsaw *a* is continually advanced and held against the object, without, however, causing any heavy frictional resistance in the machine itself by such advancement.

Having now described my invention, what I claim as new, and desire to protect by Letters Patent, is—

1. In a new and improved band-saw the 40 combination of a sawing-band with spiral actuated means for operating and advancing said sawing-band substantially as described.

2. In a new and improved band-saw, the combination of a sawing-band, rollers carrying said band, shafts in connection with the 45 said rollers, means for giving said shafts a rotary movement, and other means for giving said shafts a lateral movement, both of said means being so arranged and combined as to generate a spiral movement in said 50 shafts, substantially as described.

3. In a new and improved band-saw, the combination of a frame, ball-bearings therein, shafts mounted in said bearings, rollers on said shafts, a sawing-band on said rollers and means in connection with said shafts adapted to give the latter a spiral actuating movement, substantially as described. 55

4. In a new and improved band-saw, the combination of a frame, ball-bearing-journaled shafts therein, rollers on the forward ends of said shafts, a sawing-band on said rollers, a pulley-wheel in said frame, gearing connecting said wheel and said shafts and a weight-actuated rod in connection with said 60 shafts, substantially as described. 65

5. In a new and improved band-saw, the combination of a frame, shafts journaled therein, rollers on said shafts, a sawing-band on said rollers, a rod suitably mounted in 70 said frame, forked arm on said rod provided with slots in the prongs of its fork, a sleeve on one of said shafts, studs on said sleeve entering said slots, racks in connection with said frame, toothed quadrants on each of said racks 75 meshing together, other forked arms on said racks engaging said shafts, a band connected with said rod, a weight on the outer end of said band and suitable mechanism for rotating said shafts substantially as described. 80

WILHELM HARTMANN.
